UNITED STATES PATENT OFFICE.

FELIX EBERHART, OF NEWARK, NEW JERSEY, ASSIGNOR TO AMERICAN CAN COMPANY,
OF NEW YORK, N. Y., A CORPORATION OF NEW JERSEY.

POWDER-CONTAINER.

1,181,651.

Specification of Letters Patent.

Patented May 2, 1916.

Application filed May 21, 1915. Serial No. 29,472.

To all whom it may concern:

Be it known that I, FELIX EBERHART, a citizen of the United States, residing in Newark, in the county of Essex and State 5 of New Jersey, have invented a new and useful Improvement in Powder-Containers, of which the following is a specification.

My invention relates in general to powder containers and has more particular reference 10 to containers provided for the packaging and use of talcum, face and other toilet powders.

A principal object of the present invention is the provision of a container of the 15 character described which will be provided with a puff disposed normally within the container, and this without interfering materially with the discharge of powder through sifter openings provided for the 20 purpose.

A further object of the invention is the provision of a container of the character described and provided with a powder puff, the sifter top provided serving as a handle 25 for the use of the puff.

An additional object is the provision of such a container and puff of simple, durable and efficient construction which may be cheaply manufactured and which will be of 30 pleasing appearance.

Other objects and advantages of the invention will be apparent as it is better understood from the following description when considered in connection with the accompanying drawing illustrating a preferred embodiment thereof.

Referring to the drawing, Figure 1 is a perspective view of a container embodying my invention; and Fig. 2 is a section thereof.

For the purpose of illustrating my invention I have shown it embodied in a talcum powder container comprising a body 3 of any preferred or usual construction. Although in the present instance this body is shown to be of flat, oval or circular form, it will be manifest that it may have any desired shape and size. At the top a ring 4 extends inwardly and it is seamed at its edges at 5 to the top of the body 3. This ring, in the present instance, forms the greater part of the top of the container. Its inner edge 6 is bent downwardly to provide a friction wall within which is frictionally seated the sifter top generally designated at 7. This top, in the present in-

stance, consists of an upwardly extending neck 8 terminating in a dome 9 provided with sifter openings 10. This dome forms a stationary part of the sifting device and is embraced by a movable part 11 also provided with sifter openings 12 which may register with the openings 10 when it is desired to sift powder from the container. Movement of these apertures out of registration closes the sifter device against sift- 60 ing. The neck 8 terminates at its lower end in an outwardly extending flange 13 beneath which is engaged a sheet 14 upon which is secured a powder puff 15. This sheet is held in place in any preferred manner, being shown on the drawing as crimped by a fold 16 in the flange 13. The provision of the crimped joint 16 provides a friction wall 17 adapted to engage with the friction wall provided at the edge of the ring 4. 70 The flange 13 beyond this friction wall terminates in a flange 18 adapted to rest upon the upper surface of the ring when the sifter device is positioned upon the body. The disk 14 is perforated centrally as is also 80 the puff 15, so that when the apertures 10 and 12 are in registration and the sifter top is in place, powder may be sifted through the puff and out in the usual manner. If desired the sifter top may be 85 grasped and lifted from its place and the puff used in the manner of any puff.

It is thought that the invention and many of its attendant advantages will be understood from the foregoing description, and 90 it will be apparent that various changes may be made in the form, construction and arrangement of the parts without departing from the spirit of the invention or sacrificing any of its material advantages, the form 95 hereinbefore described being merely a preferred embodiment thereof.

I claim:

1. A container for talcum powder and the like comprising a receptacle, a removable sifter cover therefor, said sifter cover being provided with a powder puff on its inner side.

2. A talcum powder container comprising a receptacle, a removable sifter top therefor, 105 said sifter top having a puff upon its under- surface provided with an aperture through which powder may pass to the sifter portion of said top.

3. A container for talcum powder and the 110

like comprising a body, a ring at the top of said body and extending inwardly thereof, a sifter top fitting within said ring and carrying on its under face a perforated powder puff.

4. A container for talcum powder and the like comprising a body, a ring at the top of said body and extending inwardly thereof, a sifter top fitting within said ring and carrying on its under face a perforated powder puff, and a sheet to which said puff is secured, said sheet being crimped at its edges to the material of said sifter top.

5. A container for talcum powder and the like comprising a sifter top provided with an upwardly extending sifter mechanism and having a powder puff upon its under face, said upwardly extending sifter mechanism serving as a handle when the puff is used.

Signed in the presence of two subscribing witnesses.

FELIX EBERHART.
